UNITED STATES PATENT OFFICE

2,446,190

INFLATABLE LEAK STOPPER

Carl A. Oding, Alameda, Calif.

Application October 29, 1945, Serial No. 625,215

8 Claims. (Cl. 114—227)

1

This invention relates to the emergency repairing of shell or bulkhead perforations in water-borne ships.

It is an object of the invention to provide an effective stopper for plugging a hole, through which water has flowed to flood a compartment, so that the flood water may be cleared out of the compartment and further emergency and seaworthy repairs to close the hole may be undertaken.

Another object of the invention is to provide a mat-type of hole stopper which may be accurately placed over the perforation it is desired to close without the assistance, outboard of the ship, of a diver or draw lines passed under the ship's hull.

A further object of the invention is to provide, in a mat-type of hole stopper, means for varying the degree of buoyancy thereof so that the descent or ascent thereof through a body of water may be regulated as desired.

Still another object of the invention is to provide a mat-type hole stopper which, after being positioned over a perforation to stop or reduce water flow therethrough, will permit sufficient displacement thereof so as to allow subsequent work to be carried on, in trimming the margin of the perforation or in the placement of more permanent repair members, without permitting an objectionable increase in the arrested flow of water through the perforation.

A still further object of the invention is to provide an inflatable mat-type hole stopper which, prior to and after use, may be compressed into a comparatively small volume capable of being stored without occupying an objectionable amount of space.

Yet another object of the invention is to provide a hole stopper of the character described which may be used repeatedly without suffering any appreciable ill effects.

It is a further object of the invention to provide a method of repairing hull or bulkhead punctures in water-borne vessels which is far less hazardous and more economical to practice than are the usual methods presently employed.

It is still another object of the invention to provide means, in a device of the character described, for varying the buoyancy of a distended envelope without materially affecting the volumetric content of the envelope.

The invention possess other objects and features of advantage which, together with the foregoing, will be specifically set forth in the detailed description of the invention hereunto annexed. It is to be understood that the inven-

2

tion is not to be limited to the specific form thereof herein shown and described as various other embodiments thereof may be employed within the scope of the appended claims.

Referring to the drawings:

Figure 1 is a vertical sectional view of a portion of a water-borne vessel illustrating the application of the device of my invention in closing a shell puncture in the vessel.

5 10 Figure 2 is a vertical sectional view of the vessel's hull, at and immediately adjacent to the puncture, illustrating the position of the stopper just prior to its release from the patched area.

15 Figure 3 is a vertical sectional view illustrating the completed hull patch.

Figure 4 is a vertical sectional view, similar to Figure 2 but to an enlarged scale, illustrating the primary position of the stopper in closing the puncture.

20 Figure 5 is a view, similar to Figure 4, showing the condition of the stopper after the flooded compartment has been evacuated.

Figure 6 is a view, similar to Figure 4, showing the stopper prior to its release and the more permanent patch in place.

25 Numerous methods have been devised for effecting temporary repairs in the under-water hull surfaces of water-borne ships which have become punctured due to coming in contact with sub-

30 surface objects or as a result of collision. The most common device employed to stop the perforation and limit the entry of sea water into the compartment beyond is a closely woven mat, composed of fibrous material such as hemp or 35 the like, of sufficient size to cover and extend beyond the border of the hole. This mat is worked into place on the outer surface of the hull by opposed lines connected to the opposite horizontal edges of the mat and passed, respectively,

40 up along the side of the hull above the hole and under the bottom of the hull and up along the opposite side thereof. After being properly located, under the direction of a diver sent over-side, the lines are tightened so as to draw the mat snugly to the hull and the flooded compartment is then pumped so as to reduce its water content to a minimum and thus lessen the impediment which the waterlogged compartment might otherwise impose on the vessel's headway.

45 50 Even though this type of repair will render satisfactory protection against complete re-flooding of the compartment, if the bilge pumps are kept in constant operation to continuously remove any water that might seep by the repair patch, the subsequent speed of the vessel must be mate-

rially reduced so that the water flow along the hull will not dangerously raise the mat away from the hole and allow sea water to pour into the compartment.

I have provided an improved device and procedure for closing punctures of the nature above described by means of which a more permanent class of repair may be effected than has heretofore been the case and the necessity of dry-docking the vessel may be deferred until it reaches its home port or one in which the most desirable facilities for making a permanent repair are available. In Figure 1, I have illustrated a vessel 7 in the hull of which a hole 8 has been punctured below the waterline 9 resulting in flooding the compartment 11. I provide a flexible envelope 12 constructed of several plies of rubberized fabric bonded together to form a comparatively thick tough skin capable of conforming itself to the contour of the hole 8, when forced thereinto, and further capable of resisting damaging abrasion by coming into contact with jagged portions of the plate bordering the hole. The envelope 12 is bonded to a central area of a disk 13, constructed of material similar to that of the envelope although somewhat thicker, the marginal portion of the disk being left free to form a peripheral flap 14. The stoppers, of course, are to be made in several different sizes and a selection is made of one which, from the report of the diver lowered into the flooded compartment, will be sufficiently large to completely cover the hole and extend materially beyond the border thereof.

Means are provided for rendering the envelope and its associated members buoyant when in the water and for varying the degree of said buoyancy so that a balance may be reached wherein the envelope may be made to sink at a very gradual and easily controlled rate. Provided at what may be termed the top of the envelope, and described more particularly as a plane intersecting the normal axis of the disk 13, is a bushing 16 secured to the envelope and through which passes, into the latter a flexible air hose 17 loosely looped therein and provided at its free end with a cork or other buoyant float 18 so as to constantly maintain the end of the hose above the level of any amount of fluid that may be introduced into the envelope. A similar bushing 19 secured to the envelope adjacent the bushing 16 provides entrance into the envelope of a flexible fluid line 21. The air and fluid lines 17 and 21 may be connected in one of several known ways to sources of air and fluid under pressure but I have chosen the apparatus shown in Figure 1 for purposes of description. This arrangement comprises a tank 22 which may be an auxiliary structure or one which is incorporated in the vessel's structure such as the boiler feed water tank which will hold a quantity of water exceeding the volumetric content of the envelope 12 when the latter is fully expanded. Extending from the bottom of the tank 22 is a supply pipe 23 connected to a T 24 having a nipple 26, co-extensive with the pipe 23, to which the upper end of the fluid line 21 is attached. A valve 27 in the pipe 23, between the T 26 and the tank 22, controls the flow of fluid from the tank into the line 21. The top outlet of the T 24 is connected to a supply line 28 controlled by a valve 29 while the opposite or bottom outlet is connected to a discharge line 31 controlled by a suitable valve 32. The air line 17 connects, at deck level, with a T 33 contained in a compressed air supply

line 34 which is controlled by a valve 36. The bottom outlet of the T 33 connects with a discharge line 37 normally closed by a valve 38. Prior to being cast overside the envelope 12 is fully distended by opening the valve 36 to permit a volume of air to enter the envelope through the line 17. Thus maximum buoyancy of the envelope is effected. This buoyancy may be now modified as desired by admitting water to the envelope and simultaneously exhausting a comparative amount of air therefrom so as to cause submersion of the envelope. This may be done in either of two ways, namely, by opening the valve 27, so as to permit water from the tank 22 to flow by gravity and under the pressure represented by the head of the water above the envelope into the latter while simultaneously forcing air from the inflated envelope through the air line and opened valve 38, or by opening the valve 29 with the same result, the valve 27 in this case being, of course, closed. Thus the degree of buoyancy in the envelope may be very finely adjusted to the point wherein the former will remain substantially suspended or will very slowly sink so that it can be maneuvered readily into the desired position to cover the puncture in the hull. It will be particularly noted from the foregoing description that during the changes in buoyancy of the envelope due to the interchange of air and water therein, the volumetric content of the envelope will be little affected.

Means is provided for accurately guiding the stopper, after it has been suitably distended, into its final position over the puncture. Positioned centrally of the disk 13 is an externally and internally threaded nipple 39 having a flange 41 thereon apertured to receive rivets 42, or their equivalent, which pass axially through the disk and are engaged with a plate 43 lying within the envelope and concentric with the flange 41. An access opening 44, provided in the wall of the envelope opposite the plate 43 and closed by a flexible plate 46 mounted in place by bolts 47 equipped with wingnuts 48, serves to permit the operations necessary in mounting the nipple flanges and rivets and to afford means for inspections or repairs which may have to be periodically undertaken inside of the envelope. During the initial entry into the flooded compartment 11 by the diver, or during a subsequent entry when the stopper and its associated apparatus have been placed in readiness, the diver passes a line 49, attached at its end to a buoyant member, outboard through the puncture 8 so that the line may rise to the surface of the water above the puncture. The float member is then detached from the line and the screw plug 51, with which the end of the line is equipped, is threaded into the nipple 39 as is best shown in Figure 4. By drawing on the line, the diver may then move the buoyancy-balanced stopper into the position indicated by the dot-dash lines of Figure 1 wherein the puncture 8 is plugged thereby. In the cases of the larger stoppers it may be necessary to use winch power to pull them into place but this may be easily done by anchoring a tackle block to a suitable structural element of the vessel, such as a bulkhead stiffener or frame, running the line through this block and continuing with the line out of the compartment through the opening or entrance manhole thereof to a point wherein it may be reached by suitable pulling means. When the stopper is in its final position, it must be held there temporarily for the reason that equalized pressure of the water exists on the sea and com-

partment sides thereof. This holding may be accomplished by lashing the line 49 to a portion of the ship's structure opposite the puncture. This done, the flooded compartment 11 may be then evacuated of water or the latter may be so reduced as to safely permit repair operations to be carried on therein. As the volume of flood water is reduced in the compartment it will be seen that a hydrostatic unbalance will be created wherein the pressure, exteriorly of the ship, on the stopper will tend to force the latter tightly against the hull and around the margin of the puncture. This will effectively seal the puncture and, except where long tears or cracks radiate from the main perforation, will completely stop the ingress of water into the ship. When once positioned, the stopper may be completely evacuated of air and sufficient water under pressure may be pumped thereinto to offset any tendency of the outboard pressure to extrude the stopper inboard through the perforation.

After the stopper has been finally placed, as described above, continued repair operations may proceed. Since the compartment 11 has now been completely or substantially cleared of water, the repair crew may descend thereinto to survey the damage and make the necessary preparations to complete the repair job. The first consideration is how large a section of plate will be required to completely cover the shell perforation and slightly overlap the undistorted portions of the shell bordering the perforation. Having determined this and the source of the repair plate 52, which may be taken from a superstructure bulkhead or other portion of the vessel which will not endanger its structural strength, the latter is secured, sized and provided at its center with an aperture 53 into which is welded a threaded pipe nipple 54. After the line 49 has been detached, following final placement of the stopper and evacuation of the chamber, a centrally apertured pusher plate 56, sized to pass through the unaltered hull perforation 8, is mounted on the nipple 39 by means of a nut 57 engaged with the external threads of the nipple. The arrangement of the parts is such that the pusher plate lies as close as possible to the face of the disk 13. A length of pipe 58 is now secured, of suitable size to pass over the nut 57 and to pass freely through the repair plate nipple 54, and is positioned as shown in Figure 5 abutting the pusher plate. The repair plate 52 is next slipped onto the pipe with the nipple 54 pointing inboard of the ship. A suitable hydraulic or screw jack is then interposed between the remote inboard end of the pipe 58 and any convenient fixed structural member of the ship spaced from and traversing the end of the pipe and pressure is applied axially of the pipe to cause the pusher plate 56 to move the central portion of the disk 13 outboard until only the peripheral flap portion 14 thereof remains in contact with the shell plate. Secure leakproof engagement of the disk in the aforesaid peripheral area will be insured by the external water pressure existing on the envelope. Pushing the envelope outwardly creates clearance on the outboard side of the curled or jagged border of the perforations sufficient to permit admittance of the tip and head of an oxy-acetylene cutting torch which is used to trim the perforation back to the point where comparatively flat shell plating exists. In this procedure, the flame and the slag stream of the torch will of course be directed inboard so as to not damage the disk 13. As

soon as the trimming operation has been completed, the repair plate 52 is slid along the pipe 58 to cover the perforation and is then secured in place by means of a peripheral weld 59 as shown, for example, in Figure 6. Upon completing the weld 59, the axial pressure on the pipe 58 exerted by the jack is relieved which permits the pipe to be dismounted and the central portion of the disk 13 to return toward the shell plating. 10 A pipe cap 61 is then threadedly engaged with the nipple 54 and the repair is completed, with the exception of removing the stopper, which may be accomplished by opening the water discharge valve 32 and by also opening the air valve 36 so as to exhaust, by the air pressure, the water in the envelope 12 to effect a buoyancy of the latter sufficient to raise it and its attached pusher plate 56, to the surface of the water from where it may be retrieved and stored for future use. 15 In the event that the disk 13 should cling so tenaciously to the shell plating so as to create a vacuum pocket therebetween, which might prevent the envelope from rising to the surface even after it was fully inflated with air, a pipe 20 62 is connected to the cap 61 and connected to a suitable source of liquid or air under pressure, a valve 63 being interposed in the line so that fluid under proper pressure may be introduced when desired into the space covered by 25 the disk 13. This will equalize the hydrostatic pressure on both sides of the envelope 12, and will effect ready separation of the envelope from the hull so that it may be floated to the surface.

Although I have chosen to describe the apparatus and method of my invention as applied to a ship it will be evident to those skilled in the art that the procedure may be employed anywhere between separate chambers wherein differences of pressure may exist or may be established and that the scope of the invention is to be limited only by the wording of the following claims.

I claim:

1. Means for arresting relative communication between a first body of fluid, lying on one side of a bulkhead having an opening therein, and a second body of fluid lying on the opposite side of said bulkhead, comprising a distendible envelope sufficiently large to cover said opening and capable of being submerged in said first body of fluid to a position in registry with said opening, means to pneumatically inflate said envelope to render it buoyant, means to displace a quantity of air in said envelope with a heavier fluid to modify the buoyancy of the envelope and thereby regulate the rate of descent thereof in said first body of fluid, and means extended through said opening from the second to the first bodies of fluid and connected with said envelope to draw the latter into position over said opening.

2. In apparatus for arresting relative communication between a first body of fluid, lying on one side of a bulkhead having an opening therein, and a second body of fluid lying on the opposite side of said bulkhead, means sufficiently large to cover said opening and adapted to be introduced into one of said bodies of fluid comprising a flexible disk to cover said opening, a distendible envelope secured to said disk, means to introduce air under pressure into said envelope to render the latter buoyant, means to admit liquid into said envelope, and means to position said disk and envelope in substantial registry with said bulkhead opening.

3. In apparatus for arresting relative com-

munication between a first body of liquid lying on one side of a bulkhead member having an opening therein, and a second body of liquid lying on the opposite side of said bulkhead member, means within said first body of fluid comprising a flexible disk for covering said bulkhead opening, a distendible envelope mounted concentrically with and on the side of said disk away from said opening, separate air and liquid lines entering said envelope, means to supply compressed air to said air line to inflate and render said envelope buoyant, and means to admit liquid to said envelope through the liquid line to displace a portion of said air therein and to exhaust said displaced air through the air line so as to modify the degree of buoyancy of the envelope.

4. Apparatus for arresting relative communication between a first body of liquid, lying on one side of a bulkhead member having an opening therein, and a second body of liquid lying on the opposite side of said bulkhead member, means within said first body of fluid comprising a flexible impermeable disk for covering said bulkhead opening, a distendible envelope mounted concentrically with and on the side of said disk away from said opening, a source of compressed air and a source of liquid under pressure, air and liquid lines connecting, respectively, the envelope with said air and liquid sources, and separate means in said air and liquid lines to, respectively, admit and exhaust air and liquid to and from said envelope.

5. Apparatus for arresting relative communication between a first body of liquid, lying on one side of a bulkhead member having an opening therein, and a second body of liquid lying on the opposite side of said bulkhead member, means within said first body of fluid comprising a flexible impermeable disk for covering said bulkhead opening, a connector mounted on said disk on the side thereof facing said bulkhead, a distendible envelope mounted concentrically with and on the side of said disk away from said opening, means to admit regulated quantities of air and liquid to said envelope to distend the latter and to vary the degree of buoyancy thereof, and means extendible through said bulkhead opening and engageable with said connector for drawing said disk against said bulkhead.

6. Apparatus for arresting relative communication between a first body of liquid, lying on one side of a bulkhead member having an opening therein, and a second body of liquid lying on the opposite side of said bulkhead member, means within said first body of fluid comprising a flexible impermeable disk for covering said bulkhead opening, a connector mounted on said disk on the side thereof facing said bulkhead, a distendible envelope mounted concentrically with and on the side of said disk away from said opening, means

to admit regulated quantities of air and liquid to said envelope to distend the latter and to vary the degree of buoyancy thereof, and a cord extendible through said bulkhead opening and having at an end thereof a member engageable with said connector for drawing said disk against the bulkhead.

7. Apparatus for arresting relative communication between a first body of liquid, lying on one side of a bulkhead member having an opening therein, and a second body of liquid lying on the opposite side of said bulkhead member, comprising, in combination, a stopper, to be immersed in said first body of liquid, having a flexible impermeable disk for covering said bulkhead opening, a distendible envelope mounted concentrically with and on the side of said disk away from said opening, a source of compressed air and a source of liquid under pressure, air and liquid lines connecting, respectively, the envelope with said air and liquid sources, means to admit regulated amounts of air and liquid to said envelope to vary the degree of buoyancy thereof in the first body of liquid, means to draw said stopper against the bulkhead over said opening and means to remove sufficient of said second body of liquid to establish a hydrostatic pressure differential on opposite sides of said bulkhead.

8. Apparatus for arresting relative communication between a first body of liquid, lying on one side of a bulkhead member having an opening therein, and a second body of liquid lying on the opposite side of said bulkhead member, comprising, in combination, a stopper, to be immersed in said first body of liquid, having a flexible impermeable disk for covering said bulkhead opening, a connector mounted on said disk on the side thereof facing said bulkhead, a distendible envelope mounted concentrically with and on the side of said disk away from said opening, means to admit regulated quantities of air and liquid to said envelope to distend the latter and to vary the degree of buoyancy thereof, means extendible through said bulkhead opening and engageable with said connector for drawing said disk against the bulkhead, and means to remove sufficient of said second body of liquid to establish a hydrostatic pressure differential on opposite sides of said bulkhead.
